PHOTOFOLASH LAMP

Paul Greger, Braunschweig, Germany, assignor to Voigtländer, A. G., Braunschweig, Germany, a corporation of Germany

Application December 8, 1953, Serial No. 396,975

Claims priority, application Germany December 22, 1952

10 Claims. (Cl. 240—1.3)

This invention relates to photoflash lamp devices and it has particular relation to photoflash lamp devices in which flash bulbs of varying dimensions can be used.

Various types of photoflash lamp devices provided with means for ejecting the flash bulb have been known previously and devices in which flash bulbs of varying sizes can be inserted in the same reflector, have also been known.

The main object of the present invention consists in providing a photoflash lamp device which comprises means for ejecting the flash bulb and comprises only one socket, but nevertheless permits the use of flash bulbs of varying sizes.

According to the present invention, this object is attained by providing the lamp socket with two or more detents, arranged one behind the other in suitable distances from the focal point of the reflector in such manner that, upon insertion of the various bulbs in the device, the individual bulbs are held by the socket in positions, in which their center of illumination coincides with the focal point of the reflector. Flash bulbs which are provided with one or two holding or retaining pins on their base, are suitable for use in the device according to the invention.

Depending on the principle utilized in ejecting the used bulbs, detents having positive action or detents acting by their form or design can be used. In the last mentioned case, detent teeth are provided on a spring biased ejector lever which, upon insertion of a bulb against the action of an ejecting spring, recedes from the socket and subsequently comes to rest with one of its teeth behind the retaining pins of the lamp base, said ejecting spring simultaneously and preferably forming the electrical bottom contact. After release of the ejector lever and the resulting release of the retaining pins of the bulb base, the bulb is ejected from the socket by the ejector spring.

In another advantageous ejector device suitable for the present invention, positively acting detents of the type shown in U. S. Patent No. 2,384,327 issued on September 4, 1945, are used.

Such positively acting detents are preferably formed by constricting or coil springs which are peripherally arranged around the lamp socket and enter the interior of the lamp socket through slots, which are located in the range of bent out grooves of the lamp socket. The effect of such springs consists in that the springs are first pressed outward by the retaining pins of the flash lamp inserted in the device and subsequently are located in front of said retaining pins as positively acting detents.

The ejecting means used in carrying out the present invention comprises an ejector lever which is disposed under the middle contact of the inserted flash bulb.

Instead of using the above mentioned constricting or coil springs, a socket can be used which has a radial proper elasticity brought about by slots, in combination with detent recesses provided in the socket proper from inside to outward direction. According to the invention, these detent recesses can have a ring shaped design, so

2

that the flash bulb can be inserted in the socket independently, or approximately independently, from the rotary position of its retaining pins.

It is a further object of the present invention to provide in the use of positively acting detents and of an ejector lever, means for permanently and automatically keeping the surface of the middle contact in polished condition.

It is also an object of the invention to use a particular current conducting arrangement over the joint of the ejector lever, whereby an elbow spring serves for conducting the current.

In the appended drawings, which illustrate by way of example some embodiments of the invention, to which the invention is not limited:

Figure 1 illustrates a photoflash lamp device showing the features of the present invention, in sectional view;

Figure 2 is the front view of the photoflash lamp device, some parts of which are shown in section;

Figure 3 is a cross-sectional view of the device shown in Figure 1, the section being taken along line III—III in Figure 1;

Figure 4 illustrates an ejector socket with a unilaterally, longitudinally slotted sleeve and an ejector lever;

Figure 5 illustrates an ejector socket with a sleeve longitudinally divided at its front end and a detent acting in all directions;

Figure 6 illustrates, in longitudinal sectional view, a photoflash lamp socket with an ejector spring and two detents acting by their design;

Figure 7 is a front view of the flash lamp socket shown in Figure 6;

Figure 8 shows the base of a flash bulb in side view, said base being provided with two retaining pins;

Figure 9 illustrates an ejector socket having a unilaterally slotted sleeve and three locking positions, and Figure 10 illustrates, in longitudinal sectional view, a photoflash lamp socket with an ejector spring and three detents acting by their design.

Referring now to the drawings in detail, in the embodiment shown in Figure 1, lamp socket 1 has a closed form which is of substantially horseshoe-shaped cross-section in this case. Laterally arranged, bent out grooves 3 of lamp socket 1, which according to a preferred embodiment, extend in straight line and parallel to axis 2 of the lamp socket, allow the insertion of retaining pins 4 of flash bulb 5, which serve as guide means and for support. Lamp socket 1 is electrically conductive at least on its inner surface and is connected with one terminal of a current source.

On the outside and around lamp socket 1, constricting or coil springs 6 are arranged at two levels, which correspond to two different inserted positions of flash bulbs and said springs prevent the inserted flash bulb from sliding out from the socket, by their lying in the ejection path of the flash bulb in front of its retaining pins. In order to attain this effect, lamp socket 1 is provided at the place of the before mentioned bent out grooves 3, with slots 7, so that springs 6 can enter the interior of the space enclosed by socket 1. In order to enable retaining pins 4 of a flash bulb to press backward springs 6 upon insertion of the bulb into the socket, the diameter of the convolutions of springs 6 is of such dimension relative to the active length of the retaining pins that an operative wedge or key drive in the direction of insertion results, in which the key wedge is formed mainly by the rounding of the springs. For the same reason, in view of suitable dimensions of slots 7, springs 6 enter the space enclosed by the lamp socket only up to about the half of the diameter of the convolutions.

In order to obtain good electric contact between the base of the flash bulb and lamp socket 1, the lamp socket

is provided with slots 8 which are staggered relative to slots 7 preferably by a right angle and springs 6 enter the space in the interior of the lamp socket through said slots 8 likewise only up to about the half of the spring diameter. In order to prevent displacement of springs 6 at these places, the lamp socket is provided here too with an outwardly extending longitudinal crease 9. Thus, upon insertion of a flash bulb into the lamp socket, for example edge 10 of the flash bulb base forces springs 6 which protrude through slots 8, in outward direction. The tension of springs 6 resulting on this side, presses the base of the flash bulb in direction 11 toward the opposite interior side of the lamp socket and produces there electrical contact 12 between the flash bulb base and the lamp socket.

In carrying out the present invention, springs 6 can be made of any suitable material, for example also of electrically non-conducting material.

The lamp socket extends in downward direction and is in fixed connection with an electrically non-conducting, fork-shaped supporting or bearing element 13, in the forked part of which a bolt 14 is fixedly inserted perpendicularly to, and at a lateral distance a from, axis 2 of the flash bulb (see Fig. 3). Said distance a is determined by the possibility of conveniently operating the ejecting mechanism. An ejector lever 15 is arranged on and capable of swinging about said bolt 14. One leg of this lever 15, which is freely accessible from the outside, forms a key or handle 16 which is movable in radial direction to axis 2, while the other leg 17 of said lever is bent in such manner that its part 18, which is designed as a contact member, remains in contact with the middle contact of the flash bulb inserted in the socket during the entire path of its swinging.

A second position of ejector lever 15 is shown in Figure 1 in dotted line. In the forked recess of member 13, a torsional spring 19 is applied to bolt 14. One end 21 of said spring 19 which is connected with current supply cable 20, is supported by edge 22 of member 13, while the other end 23 of spring 19 bears against the electrically conducting interior surface 18 of leg 17 of lever 15 and forms an electrical contact therewith. The effect of torsional spring 19 is determined in such manner that this spring provides, on the one hand, for safe contact between part 18 of lever 15 and the middle contact of the flash bulb inserted in the lamp socket, while, on the other hand, the effect of this spring by itself is not capable of ejecting an inserted flash bulb against the effect of spring 6 located in front of retaining pins 4.

Upon insertion of a flash bulb 5 in socket 1, the suitably bent contact part 18 of ejector lever 15 is displaced at a suitable position of lever 15, to a small extent relative to the middle contact of the bulb and perpendicularly to axis 2, whereby a certain polishing effect and bright condition of this contact automatically result. In order to increase this effect, contact part 18 can be made file-like on its surface turned toward the middle contact of the bulb. The same result can be obtained by a drilling movement of the middle contact of a flash bulb relative to said contact part, for example by forming bent out grooves 3 not in straight line, but entirely or partially as a helical groove.

Ejection of the inserted flash bulb is brought about by applying pressure to member 16 of lever 15 in the direction of arrow 24, in order to overcome the locking or arresting effect of springs 6.

The lamp socket proper is connected with reflector 25 by a common supporting member 26.

Figure 4 illustrates a lamp socket 27, in which an ejector lever 29 is pivotally arranged in insulating member 28. Arm 30 of lever 29 projects through opening 31 into the interior of the lamp socket. The latter has the form of a sleeve, slit at one side, whereby the two flaps 32 and 33 of the socket are rendered capable of a spring effect and of holding the retaining pins of an in-

serted flash bulb by means of detent notches 34 provided in the sleeve proper. Above or in front of said notches 34, a wedge-shaped stamped portion 36 is provided in border portion 35 of elastic flaps 32, into which the retaining pins of a flash bulb are inserted, whereby the spring effect of flaps 32 and 33 is utilized.

Under notches 34, a terminal stop 340 projecting into the interior 31 of the sleeve, is provided on both sides of the sleeve in order to prevent the bulbs from being inserted too far.

In inserting a flash bulb into a lamp holder, the flash bulb is guided in such a manner that the retaining pins 4 (see Fig. 1) arranged on the base part of the flash bulb, enter the wedge-shaped stamped portions 36. If the flash bulb is then inserted in the lamp holder, the two flaps 32 and 33 of the lamp holder exert their spring effect. The lower frontal surface of the flash bulb comes in contact with arm 30 of the ejector lever 29, which projects into the insertion path of the flash bulb, already before the retaining pins 4 enter the first detent notches 34, and starts to cause swinging of the ejector lever 29 about its pivot. Thereby, the free arm of ejector lever 29, which projects from the lamp holder, withdraws from insulating part 28. The swinging of the ejector lever 29 is more or less extensive, depending on at which of the detent notches 34 the inserting movement is terminated. In order to eject a flash bulb from the lamp holder, the swung-out free arm of the ejector lever 29 is actuated in such a manner that its arm 30, which extends below the flash bulb, exerts pressure on the lamp base. Thereby, retaining pins 4 are removed from the detent notches 34. When the ejector lever 29 has been moved up to the position shown in Fig. 4, arm 30 of ejector lever 29 will have caused removal of the flash bulb from the lamp holder to such an extent that the retaining pins 4 arranged on the lamp base will be located in the wedge-shaped stamped portions 36. The flash bulb will be then in a position in which it can be easily removed from the lamp holder, or falls from it by itself if the flash lamp device is held in a corresponding position.

In the device shown in Fig. 4—in a manner similar to that described in connection with Figs. 1, 2, and 3—lamp socket 27 is electrically connected by means of a cable with one pole of the electric source. A second cable connected with the other pole of the electric current source, is connected in a manner similar to that described in the preceding example, to the ejector lever 29, which is electrically insulated from the lamp socket 27 by means of an insulating member 28. A flash bulb 5 inserted in the lamp socket lies with its lower bottom contact against the ejector lever 29. The retaining pins 4 seated on the base of the flash bulb are in contact with the interior surfaces of the detent notches 34. In this manner an electrical connection between the current source and the flash bulb 5 is brought about.

Figure 5 shows a sleeve 37, which likewise carries an ejector lever 29 pivotally arranged on insulating member 28. One arm 30 of lever 29 projects into the interior 31 of sleeve 37 of the lamp socket and engages there the inserted flash bulb from below. Sleeve 37 is slotted from above on two opposite sides, so that its upper portion is formed by two halves 38 and 39, which can be elastically moved apart. In the range of its flaps, sleeve 37 has two creases 40 of semicircular shape, arranged one above the other, into which retaining pins of an inserted flash bulb can enter. An edge portion 41 of the flaps, which extends outwardly conically over the entire periphery, causes the flaps to move elastically apart, upon insertion of a flash bulb. The structure of this device has the advantage that a flash bulb can be inserted in the socket approximately independently from the rotary position of its retaining pins.

In the lamp holder illustrated in Fig. 5, the lower frontal surface of the flash bulb likewise contacts ejector lever arm 30, which projects into the path of insertion,

already before the retaining pins 4 (see Fig. 1) provided on the base of the flash bulb, enter the first crease 40 of semi-circular shape. Thus, upon insertion of a flash bulb, the free arm of ejector lever 29, which projects from the lamp holder, is caused to swing. In order to eject a flash bulb from the lamp holder, said free arm is operated in such a manner that ejector lever arm 30, which extends under the flash bulb, exerts pressure on the bottom surface of the flash bulb and causes removal of the latter from the lamp holder.

In Fig. 5, the sleeve 38 is again connected with one pole of the current source, while the other pole of the current source is in electrical contact with ejector lever 29, which is insulated from sleeve 38 by an electrically insulating member 28. Thus, a flash bulb inserted in sleeve 38 will be in electrical contact with the current source through the bottom contact of flash bulb 5 which contacts ejector lever 29 and the retaining pins 4 of flash bulb 5, which lie against the interior wall of the semi-circular crease 40.

Figures 6 and 7 illustrate a lamp socket having two detent positions for flash bulbs of different sizes, in longitudinal section and in front view, respectively, said socket being provided with detents and an ejector spring.

In the embodiment shown in these figures, the bottom of socket 42 consists of an insulating member 43, in which an ejector pin 44 is displaceably arranged and urged to advanced position by spring 45. This spring is designed and dimensioned in such manner that it serves as an ejector spring, and, by electrical connection with one electrical terminal and in combination with ejector pin 44, it serves simultaneously also as an electrical bottom contact. Sleeve 42 is provided at two oppositely arranged points with slots 46 for guiding the retaining pins 4 of flash bulb 5. An ejector lever 49 is pivotally arranged at 48 on sleeve 42. One arm 47 of lever 49 is provided with two saw teeth 50, which constitute detents acting by their design, and project through one of said slots 46 into the interior of sleeve 42. Inward movement of said arm 47 is limited by stop bolt 51, by which the ejector lever 49, which is under the effect of spring 52 abuts at the outer wall of the sleeve when the socket is empty. Thereby, saw teeth 50 of lever arm 47 point with their inclined surface upward, while their other, inner edge is directed perpendicularly to the longitudinal axis of sleeve 42.

Upon insertion of retaining pins 4 of a flash bulb 5 into longitudinal slots 46 of sleeve 42, one of the retaining pins 4 passes over the inclined surface of first saw tooth 50 of ejector lever 49 and presses said tooth backward, whereupon said tooth comes to lie with its radially extending edge in front of one of retaining pins 4. It is within the scope of the present invention to arrange a second, similar ejector lever on the other side of the sleeve.

A larger flash bulb is inserted in sleeve 42 further, i. e. until it reaches, and is locked by the second saw tooth, in a manner similar to that described above. After releasing members 50 by pressing ejector lever 49 in the direction of arrow 53, the inserted bulb is ejected by ejector pin 44 from the socket, under action of spring 45.

In connection with Figs. 6 and 7, it will be understood from the above that the ejector pin 44 arranged in insulating member 43 and thus also the bottom contact of a flash bulb 5 inserted in the device, is in electrical contact with one pole of the current source. The other pole of the current source is connected with sleeve 42. Thereby the locking lever is supplied with current and provides, over its saw teeth 50, electrical connection with the retaining pins 4 of the base of flash bulb 5. Simultaneously, locking lever 49 urges the base of flash bulb 5 against the interior wall opposite thereto, of sleeve 42, so that here too electrical connection between flash bulb 5 and sleeve 42 is brought about.

Figure 8 illustrates the base of a flash bulb, adapted to be used in a lamp socket according to the present invention. Said base is provided with two retaining elements 4, which consist, for example, of pins, but may also be studs which are stamped from the sleeve forming the base.

Figure 9 illustrates a lamp socket, the structure of which is generally similar to that shown in Figure 4, but differs from the latter by the presence of three detents 54, which enable the socket to be used for receiving and holding bulbs of three different sizes. The other reference symbols in Figure 9 have the same meaning as in Fig. 4.

Insertion and ejection of a flash bulb takes place substantially in the same manner as already described above in connection with Fig. 4. As in this case, in contrast to the lamp holder shown in Fig. 4, three detents 54, arranged one after the other, are provided, the free ejector lever arm, which projects from the lamp holder, will continue swinging only when a flash bulb is inserted in the lamp holder to such an extent that its retaining pins enter the lowest of the three detents 54.

In the device shown in Fig. 9, the electrical connection between a flash bulb 5 inserted in the lamp socket and the current source corresponds to the arrangement described in connection with Fig. 4. One pole of the current source is thereby connected to the ejector lever 29, while the lamp socket 27 is connected to the other pole of the current source.

The lamp socket illustrated in Fig. 10 is generally similar to the socket shown in Figure 6. However, in combination with the socket shown in Figure 10, two ejector levers 55, 55 are arranged in diametrically opposite positions. Each of these ejector levers is provided with three saw teeth 56, which act as detents, so that the socket shown in Fig. 10 can be used for flash bulbs of three different sizes. The two ejector levers 55 can be operated to release the saw teeth by pressure simultaneously applied in the direction of both arrows 57. The use of two ejector levers prevents canting of the flash bulb in its locked position. The other reference symbols in Figure 10, have the same meaning as in Figure 6.

In the device illustrated in Fig. 10, the electrical connection between a flash bulb 5 inserted in the lamp socket and the current source, corresponds to the arrangement described above in connection with Figs. 6 and 7. Thereby, the ejector pin 44 is connected with one pole of the current source while the other pole of the current source is electrically connected to sleeve 42, whereby the two locking levers 52, which are in contact with retaining pins 4 of flash bulb 5, likewise receive current. Between these two parts there will be electrical connection at any point, at which the lamp base and the sleeve 42 are in contact with each other.

It will be understood from the above that this invention is not limited to the specific designs, constructions, steps and other details specifically described above and can be carried out with various modifications without departing from the scope of the invention as defined in the appended claims.

What is claimed is:

1. A photographic photoflash device for receiving flash bulbs having a base member with a plain surface provided with retaining pins, and having two electric contacts, one of the contacts including the base member and the other contact being disposed at the bottom of the base member and insulated therefrom, said photoflash device comprising a socket for the base member of a flash bulb, a reflector forming a structural unit with said socket, said socket having at least two detent means for retaining flash bulbs inserted into said socket, said detent means being arranged at varying depths, one below the other in the direction of the longitudinal axis of said socket, only one of said means being adapted at a time to engage the retaining pins provided on the base of a

flash bulb inserted to corresponding depths in the socket, the distances between the respective detent means and the focal point of the reflector being such that when lamps of predetermined different sizes are inserted into said base, the filaments of the respective size lamps are disposed at the focal point of said reflector, a pair of conductors adapted to be connected to a source of electric energy, a spring biased member electrically insulated from said socket and electrically connected to one of said conductors, said spring biased member engaging the lower contact of an inserted flash bulb, means for connecting the other of said conductors with said socket which is in electric contact with the base of the inserted flash bulb and the retaining pins, and means for ejecting an inserted flash bulb, said spring biased member forming a part of said ejector means.

2. The combination in accordance with claim 1, further comprising a pair of longitudinally extending slots for slidably receiving the retaining pins of the flash bulb, said detent means comprising a plurality of further slots extending circumferentially about said socket and intersecting said pair of slots, and helical spring means positioned in each of said further slots and extending into said socket a sufficient distance to intercept the pins on a flash bulb.

3. The combination in accordance with claim 2, wherein said helical spring means extend into said socket a distance approximately equal to their radii.

4. The combination in accordance with claim 2, wherein said ejector means comprises a lever having a first arm extending into said socket and a second arm disposed exteriorly of said socket, means for pivoting said lever about an axis perpendicular to the longitudinal axis of said socket, means for insulating said lever from said socket, said lever being spring biased so that said first arm constitutes said spring biased member.

5. The combination in accordance with claim 1, wherein said socket constitutes two hollow-semi-cylindrical members, means for resiliently biasing said members one toward the other, and wherein said detent means each includes a radially enlarged, circumferentially extending groove in each of said members.

6. The combination in accordance with claim 5, wherein said ejector means comprises a lever having a first arm extending into said socket and a second arm disposed

10

15

20

35

40

45

exteriorly of said socket, means for pivoting said lever about an axis perpendicular to the longitudinal axis of said socket, means for insulating said lever from said socket, said lever being spring biased so that said first arm constitutes said spring biased member.

7. The combination in accordance with claim 1, wherein said socket has a longitudinal slot extending at least to the depth of all of said detent means, said detent means comprising longitudinally extending corrugations aligned with the pins of the base of a flash bulb to be inserted therein.

8. The combination in accordance with claim 7, further comprising a plurality of outwardly extending wedge-shaped flanges formed adjacent to the open end of said socket and aligned with said corrugated portions.

9. The combination in accordance with claim 8, wherein said ejector means comprises a lever having a first arm extending into said socket and a second arm disposed exteriorly of said socket, means for pivoting said lever about an axis perpendicular to the longitudinal axis of said socket, means for insulating said lever from said socket, said lever being spring biased so that said first arm constitutes said spring biased member.

10. The combination in accordance with claim 1

25 wherein said socket comprises longitudinally extending slots aligned with the pins on a flash bulb to be inserted therein, at least one lever aligned with one of the slots, spring means for urging said lever into said slots, said detent means comprising a sawtooth surface on said lever, said sawtooth surface extending into said socket through said slots and having at least two outwardly and upwardly extending portions terminating at their lower edges in radially extending surfaces.
